AUTOMATIC LUNG VENTILATOR

Douglas James Warner, Berkeley, and Arnold Wolf, Los Angeles, Calif., assignors to Veriflo Corporation, Richmond, Calif.

Filed Apr. 1, 1971, Ser. No. 130,546

Term of patent 14 years

Int. Cl. D24—02

U.S. Cl. D83—1

FIG. 1

FIG. 2

FIG. 4

FIG. 3

FIG. 5

FIG. 6

FIG. 7

FIG. 8

FIG. 1 is a front elevational view of an automatic lung ventilator showing our new design;

FIG. 2 is a side elevational view of the same looking from the left-hand side of FIG. 1;

FIG. 3 is a side elevational view looking at FIG. 1 from the right;

FIG. 4 is a view looking in the direction of the arrow 4 in FIG. 3;

FIG. 5 is a top plan view of the same;

FIG. 6 is a bottom plan view of the same;

FIG. 7 is a perspective view of a modified embodiment of the automatic lung ventilator disclosed in FIG. 1; portions of the ventilator are shaded to indicate contrasting color; and

FIG. 8 is a rear perspective view of the same.

We claim:

The ornamental design for an automatic lung ventilator, substantially as shown and described.
